ALBERT Rafter, of Belleville, New Jersey, assignor, by mesne assignments, to said Albert Rafter and John C. Rafter, Jr., both of Belleville, New Jersey

MACHINE FOR BENDING SHEET METAL SHAPES

Application filed December 8, 1928. Serial No. 324,706.

This invention relates to machines designed for the purpose of bending sheet metal plates into desired shapes.

Machines of the type herein described, 5 are very heavy, usually ranging between 30,000 and 40,000 pounds in weight, occupy very considerable space, consume a large amount of power, and attain a height in the neighborhood of ten feet. Heretofore, such 10 machines have been provided with solid metal beds and solid hammers with rigid solid metal side supports. However, this structure has been found objectionable in that, the solid metal bed and the solid metal 15 hammer often crack when subjected to the tremendous stresses common in the stamping operation; also the metal side pieces, when subjected to continued reversal of stresses, become brittle and crack. In view of the 20 tremendous size of these machines and their parts, it is obvious that the cracking of a bed plate or a hammer presents a serious problem inasmuch as such parts of the machine may not be readily replaced.

25 It is therefore, an object of this invention to provide a bending machine in which the bed and the hammer are so designed as to eliminate the danger of cracking when subjected to the tremendous stresses incidental 30 to a stamping operation.

These and other objects are attained by the novel construction, combination and arrangement of parts hereinafter described and shown in the accompanying drawings, 35 constituting a material part of this disclosure and in which:

Figure 1 is a rear view of the stamping press.

Figure 2 is an end view of the machine.

40 Figure 3 is a view taken on line 3-3 of Figure 1.

Figure 4 is a view taken on line 4-4 of Figure 1.

45 Figure 5 is a view taken on line 5-5 of Figure 4.

Referring to the drawings, the machine is shown to have a bed 6 of cast steel, which cooperates with a cast steel hammer 7 to stamp sheet metal into desired shapes. Se- 50 cured to the rear of the bed are guides 8 and

9. Fixed to the guide 9 is a bracket 10, which supports an electric motor 11, the latter driving, through a belt 12, the main drive shaft 13. A bracket 14 fixed to one end of the bed is provided with a bearing 15 in which is journalled one end of the drive shaft 13, the remainder of the shaft being journalled in a bearing 16 on the guide 9, and in a bearing 17 carried by a bracket 18 fixed to the rear of the bed. 55

A gear 19 fixed to the shaft 13 adjacent the bearing 17 meshes with a larger gear 20 fixed to a shaft 21 journalled in bearings 22, 23 and 24 respectively carried by the bracket 18 and the guides 8 and 9. Fixed to ends of shaft 21 are gears 25 and 26 which drive the large gears 27 and 28, respectively. 60

The gear 28 is fixed to a short shaft 29, to which is fixed an eccentric 30 having a 70 bead 31 which lies in a groove in a two-part bronze bearing 32 which lies within a collar comprising two parts 33 and 34, which are bolted together. The lower part 34 is integral with a connecting rod 35 75 which has an aperture 36 to receive bolts by which straps 35a may be connected to the connecting rod 35 and the sides of a yoke 37, the latter being also provided with bolt holes 38 and 39. 80

The lower end of connecting rod 35 is arcuate in shape and rests in an arcuate groove in a cushion block 40 positioned in the lower part of yoke 37. The bed will be seen to have a plurality of longitudinal and transverse webs 41 and 42 which are cut away at 43 as shown in Figure 1 to accommodate the eccentric collar. The sides of the bed are flanged at 44 and have bolted thereto the flanges 45 of bearings 46 and 47 for the shaft 29. Since the space between the eccentric collar and the end of the bed is greater than the length of bearing 47, washer plates 48 are attached to the ends of bearing 47. 85

90 Fixed to the front side of the bed plate are guides 49 which cooperate with the guides 8 and 9 to control the path of movement of the hammer 7. Since the distance between the sides of yoke 37 is greater than 100

the width of the hammer, bearing plates 50 are bolted to the hammer to compensate for the difference in the width. Referring to Figure 4, it will be seen that the hammer has 5 at each of its ends a threaded bolt 51 attached thereto which is in threaded engagement with a nut 52 having flanges 53 bearing against the lower side of collar 54 integral with the upper end of yoke 37. The 10 upper end of the nut 52 is keyed to a worm wheel 55 to rotate therewith, and the worm wheel engages a worm 56 which may be manipulated by a hand wheel 59. With this structure, the height of the hammer may be 15 adjusted by rotating the worm 56 which in turn rotates the worm wheel 55 and collar 52, the latter being restrained from longitudinal movement and due to its threaded engagement with bolt 51 causes the latter 20 to move longitudinally upward or downward as may be desired to adjust the height of the hammer.

As will be seen from Figure 4, the hammer comprises substantially an I-beam with its 25 central web projecting at 57 to support a die which cooperates with a female die positioned in a groove 58 in the bed, (not shown).

It will be noted that the yoke structure 30 37, as well as the eccentric shaft arrangement above described is the same at each end of the machine; also the threaded bolt and nut means for adjusting the height of the hammer are the same at each end of the 35 hammer.

In operation, power is derived from the electric motor 11 to rotate the large gear 40 wheels 27 and 28 which in turn rotate the stud shafts 29 at each end of the machine to 45 rotate the eccentrics fixed to said shafts, which in turn cause the yokes to alternately rise and fall, carrying the hammer with it to perform the stamping operation.

From the above description it will be seen 45 that there has been provided a machine which enables the bending of pieces of sheet metal of greater length than the machine, as such pieces of sheet metal may be introduced to the machine from the ends by passing between the sides of the yoke 37. This has heretofore been impossible with other stamping machines, since the end pieces of such machines have been solid and provided with no apertures through which the material to 55 be stamped could be passed.

It will also be noted that the manner in which the hammer is mounted on the yoke and the structure of the yoke itself eliminates danger of damage to the yoke due 60 to reversal of stresses during the bending operation, as the yokes are subjected to a large stress only during the raising of the hammer.

Also the web structure of the hammer and 65 the bed enable those parts to more readily

accommodate themselves to various large stresses without damage, than is the case when the hammer and bed plate are solid.

The arrangement of the bed and yokes 70 enables the driving mechanism to be carried entirely on the bed, thus eliminating obstructions in the path of the hammer so that the latter may be designed to have maximum strength for a given weight. By mounting the driving mechanism on the bed, 75 the machine is complete for operation under all circumstances and may be efficiently operated upon uneven foundations.

In machines having solid side pieces, the 80 force of the blows of the hammer causes a twisting and reversal of stresses in the side pieces with the result that the latter frequently crack. But with the yoke structure described herein the blow of the hammer is taken largely by the bed and the 85 block 40 with the result that there is practically no twisting or reversal of stresses in the yokes 37.

In order to prevent the likelihood of twisting 90 in the guides 8, 9 and 49, the upper ends of said guides are connected by bars 62.

The foregoing disclosure is to be regarded 95 as descriptive and illustrative only, and not as restrictive or limitative of the invention, of which obviously an embodiment may be constructed including many modifications without departing from the general scope herein indicated and denoted in the appended 100 claim.

Having thus described my invention, what I claim as new and desire to secure by Letters Patent, is:

In a bending machine, a bed, rear and front guides fixed to the bed, yokes at the 105 ends of the bed, a hammer mounted on the yokes, said hammer being slidable in the guides, shafts mounted at each end of the bed, eccentric members fixed to said shafts, said eccentric members being connected to 110 the yokes to reciprocate the latter when the shafts are rotated, and means supported by the rear guides to rotate the shafts.

This specification signed this sixth day of December, 1928.

ALBERT RAFTER.
